UNITED STATES PATENT OFFICE.

SALVATORE SPANO, OF ENSLEY, ALABAMA.

PADLOCK.

Application filed March 19, 1927. Serial No. 176,787.

This invention relates to improvements in padlocks and is adapted for use on barns, garages, railroad car and the like.

An object of my invention is to provide a padlock having a shackle rigidly attached to, or integral with, the lock casing, thereby forming the desired strength of construction.

Another feature of my invention is to provide a shackle so designed as easily to engage two or more eye-bolts, hasps or staples located in a spaced relation on relatively separable elements.

A further object of my invention is to provide such a padlock which is inexpensive, simple in construction and will not readily get out of order.

My invention comprises further novel features, details of construction, and combination of parts, as will be hereinafter set forth, shown in the drawings and claimed.

In the drawings:—

Fig. 1 is a plan view of the padlock in an unlocked position, with the front plate of the casing removed.

Fig. 2 is a fragmentary plan view of the lock mechanism in its unlocked position.

Fig. 3 is a fragmentary plan view of the lock mechanism illustrating the relative position of the key at the completion of the locking movement.

Fig. 4 illustrates the lock in service with the lock arm in closed position between the eye bolts.

Referring to the drawing, in which similar numerals of reference indicate the same parts, the casing comprises a front plate 5, a back plate 6 and a side member 7 which are secured rigidly by rivets 8. A bolt 9 is slidably mounted in guide members 10 which are formed on plate 11, said plate being secured

to the back plate 6 by rivets 12. A pin 13 and a segment 14 are formed on the plate 11 to engage the key 15 and are employed to resist the insertion of a foreign key. A

curved spring catch 16 notched at one side is secured to the back plate 6 and engages a shouldered notch 17 formed in the bolt 9 when said bolt is in locked position. A U-shaped shackle 18 is secured at one side

to the back plate 6 and the out-turned ends 19 of the side member 7 by means of rivets 20 and the other side of the shackle is adapted to be inserted through the eye bolts 21 and 22 mounted in the doors 23 and 24, and

through one end of a lock arm 25. This lock arm is free to swing on the shackle 18 as a pivot.

In the locking operation, the shackle 18 having been inserted through the eye-bolts 21 and 22 and then through a hole 36 in the arm 25, the latter is swung to cause a catch lug 26 formed on the arm and fitted with a bolt hole 27 to be inserted through a slot 28 in the front plate 5. When the key 15 is turned one revolution, to a semi-locked position, an offset 29 thereon engages a lug 30 and slides the bolt 9 through the bolt hole 27 in the lock arm. The offset 29 engages the lug 31 during a second revolution of the key and moves the bolt 9 a step further, thereby permitting the spring catch to snap into locked position behind the shoulder of notch 17, thereby causing the spring catch 16 to secure the bolt.

The padlock is opened by turning the key 75 reversely to the locking movement thereby causing the offset 29 to raise the spring catch 16 and then to move the bolt 9, by means of the lug 31, into a semi-locked position. A second revolution of the key 15 will slide 80 the bolt 9, by means of the lug 30, into a full open position, thereby releasing the lock arm 25 to be swung open, whereupon the lock and shackle can be removed and the door opened. Generally I prefer to place the lock 85 arm between the eye bolts, as shown in Fig. 4, as that arrangement uses the eye bolts to hold the lock arm against being tampered with on the shackle.

Although I have described and illustrated 90 a particular design, construction and arrangement of parts, I do not wish to be limited thereto except as noted in the appended claims.

Having thus described my invention, what 95 I claim as new and desire to secure by Letters Patent, is:—

1. A padlock comprising a lock casing rigidly mounted on a U-shaped shackle, in combination with a lock arm having means to detachably mount it pivotally on the shackle, and a bolt in the casing and engaging the lock arm to secure the arm in locked position on the shackle, the shackle being adapted to be inserted through elements secured to the 100 several parts to be locked.

2. A padlock comprising a lock casing having front and back plates and a marginal wall

out-turned at its ends and secured to said plate, a rigid U-shaped shackle having one end secured to the out-turned portions of the marginal wall, the free leg of the shackle 5 being adapted to be inserted through retaining members in the elements to be locked, and a lock arm removably and pivotally mounted on the free leg of the shackle and means co-acting with the padlock to lock the arm in 10 position on the free leg of the shackle.

3. In a padlock, a lock arm, a sliding bolt adapted to engage the arm and having two lugs and a lock shoulder, a spring adapted to interlock with the shoulder and having its 15 free end bent into position adjacent to the lugs, said lugs being so positioned that a key having a notched actuator, in the first revolution thereof, engages one bolt lug and moves the bolt toward locked position and 20 by further rotation engages the second lug and moves the bolt to fully locked position, and a single reverse rotation of the key dis-

places the spring and fully unlocks the bolt, substantially as described.

4. A padlock comprising a lock mechanism, a lock casing, a U-shaped shackle rigidly attached to the casing, a lock arm pivotally mounted on and removable from the free leg of the shackle, and means included in the lock mechanism and adapted to engage the arm to lock the arm against removal from the shackle, as and for the purposes described. 25

5. A padlock according to claim 4, in which the lock mechanism comprises a sliding bolt 30 with a lock shoulder, a bent spring adapted to overlap the bolt and to interlock with the shoulder, and spaced lugs on the bolt so positioned that a key will successively engage said lugs by more than one complete revolution 35 to move the bolt in one direction to lock said lock arm. 40

In testimony whereof I affix my signature.
SALVATORE SPANO.
